UNITED STATES PATENT OFFICE

WILLIAM SPENCER BOWEN, OF WESTFIELD, NEW JERSEY

COOLING SYSTEM FOR FLUID-ACTUATED TURBINES

Application filed October 27, 1927. Serial No. 229,065.

The invention relates to a cooling system for the rotor members of gas-actuated turbines as well as to the novel arrangement of governing the turbine by the medium employed for said cooling operation. It has for its object a simple and effective means for introducing, circulating and withdrawing a suitable cooling medium through the rotat-
ing members of a gas-actuated turbine of the reaction type; also, to utilize the circulated cooling medium in the governing of the velocity of rotation of its rotor portion.

To this end, the invention comprises circulating means for a suitable cooling fluid and actuated, for example, by the rotation of the turbine shaft which is provided with longitudinal ducts for conveying the fluid to and from the rotor portion of the turbine, said circulating means serving to seal the opposite ends of a casing surrounding the rotor portion and mounted about the turbine shaft. The circulating means, moreover, are in communication on the pressure side with a novel pressure-actuated governing device whereby the admission of an expansible gaseous medium for actuating the turbine is controlled.

The nature of the invention, however, will best be understood when described in connection with the accompanying drawings, in which:

Fig. 1 is a part front elevation and part vertical section illustrating a reaction turbine equipped with the novel cooling apparatus and governing device.

Fig. 2 is a transverse vertical section thereof, taken on the line 2-2, Fig. 1, and looking in the direction of the arrows.

Fig. 3 is a front elevation, Fig. 4 a fragmentary vertical section, and Fig. 5 a developed section of one of the rotor elements employed in the turbine and showing, also, the passages for circulating the cooling medium therethrough.

Fig. 6 is a vertical section, and Fig. 7 an elevation, of the novel governing device adapted to be actuated by the cooling medium circulated through the rotor portion of the turbine.

Referring to the drawings, 10 designates a

suitable frame or bed plate for rotatably supporting a shaft 11 on which are mounted rotor elements constituting a turbine of the reaction type, for example, embodying the two rotatable elements 12. These rotor ele- 55 ments are substantially of the nature set forth in my copending application Serial No. 217,146, filed September 21, 1927, which matured into United States Letters Patent No. 1,681,607, and comprise suitable disk mem- 60 bers having on one face arcuate passageways or channels 13 and on the other face radially disposed passageways or ports 14 for conducting the expansible fluid, such as gases of combustion, from a central distributing space 65 15 to substantially the circumference of the disk. From this point the fluid supplied on one face is discharged through suitable ex- 70 panding nozzles 16 to the opposite face and into the channels 13 thereof which are of di- 75 minishing cross-sectional area, all of which is more fully set forth in my said copending application.

In accordance with the present invention, provision is made for circulating about the 75 radially disposed passageways 14 and the nozzles 16 at the outer ends thereof a suitable 80 cooling medium, such as oil, the latter being supplied through a longitudinal duct 20 of the shaft 11 and port 21 therein. The coast- 85 ing surface of the surrounding rotor disk mounted on the shaft is provided also with a circular chamber 22 to receive the cooling liquid; and from the same a suitable pair of ducts 23, located upon one side of a disk, ex- 90 tend radially outwardly to a corresponding nozzle portion, conveying the cooling liquid about said nozzle and returning through a further pair of ducts 24 located upon the op- 95 posite side of said disk. The latter pair of ducts communicates through a circular re- ceiving chamber 25 about shaft 11 and a port 26 therein with a further longitudinal duct 27 of the shaft, and through a further port 28 of said shaft with the intake cham- 95 ber 29 of centrifugal pumps serving to draw and deliver the cooling liquid, which is supplied to the duct 20 through a pipe 30, to an outlet pipe 31. This pipe communicates 100 with a cooling device 32 of any suitable na-

ture, whereby the heat of the cooling liquid abstracted from the rotor members of the turbine is removed from said liquid so that as the same is again returned through pipe 30 and to the interior of shaft 20 it is at a sufficiently reduced temperature to effect the desired cooling of the rotor elements of the turbine.

The turbine is surrounded by a suitable inclosing casing 35 mounted about the shaft 11; and the fluid medium for actuating the same is introduced to the rotor elements of said turbine through a passageway 36 disposed between the same and formed by the stator portions 37 of the turbine, while the exhaust from said rotor elements which is discharged into the surrounding chamber is removed through the exhaust pipe 38 in communication therewith. It will be observed, also, that the ends of the casing 35 are sealed by the provision of the pressure, or rather vacuum, producing means constituted partly by a portion of said casing at each end thereof.

In order to control the admission of the actuating fluid medium to the said turbine, a suitable pressure-actuated governing mechanism may be provided; and in the present instance the same is indicated as mounted on the top of the casing 35, the actuating fluid medium controlled thereby being supplied by inlet pipe 39. The pressure for actuating said governor is obtained through a pipe 39' connected thereto and in direct communication with the supply pipe 30, the existing pressure of the fluid therein being determined by the velocity of rotation of the centrifugal pump members which, in turn, is a function of the rotational velocity of the shaft 11 of the turbine.

40 A convenient governor mechanism for this purpose is indicated in Figs. 6 and 7 and comprises a cylindrical member 40 having a hollow lower portion 41 in which slides a sleeve valve 42 provided with circularly disposed ports 43. The latter are adapted to register with inlet ports 44, similarly disposed circularly about the upper portion of said valve in the wall of cylinder 40 and in communication with a fluid supply chamber 45. By this arrangement, the supply chamber 45 will be placed in communication with the interior of the valve 42 when the latter is sufficiently elevated to cause ports 43 and 44 to register; and the said interior in turn communicates with the inlet passageway 36 to the turbine, the extent of elevation of said valve determining the amount of fluid medium supplied thereto.

46 A piston rod 46 extends upwardly from the top of the valve 42, which is balanced by having openings 47 therethrough; and at its upper end, the said piston rod is attached to a piston 48 which, in turn, is connected to a stem 49 projecting through the top of cylinder 40 and connected with the arms 50

of a toggle device. Provision is also made through the inlet pipe 39' for subjecting the upper face of the piston 48, for example, to the cooling fluid pressure, so that the particular degree of pressure prevailing thereon will determine the position of the valve 42 at the lower end of said piston 48. A counter pressure is provided by means of the coil spring 51 secured between the lower movable portion of the toggle mechanism and the top of a superstructure or framing 52 therefor. This spring normally tends to draw the stem 49 upwardly and with it the piston 48 and at the same time spread the toggle arms 50. When the pressure in pipe 39', and thus exerted upon the piston 48, becomes sufficiently great to extend the said spring 51 the necessary extent to bring the opposite and pivoted arm portions of the pairs of toggle elements 50 into a common plane, the valve 42 will entirely cut off the supply of gaseous medium; and this position will be maintained due to the locking position of the toggle arms when thus lying in the same plane. Springs 53, of combined lesser strength than the spring 51 and normally tending to bring the said arms together, will further insure this locked position. The turbine is thereby positively shut down as a result, for example, of an excessive speed condition, and must be manually restarted by releasing the toggle mechanism of the governor.

I claim:

1. The combination with a gaseous reaction turbine including a rotor element and rotatable shaft on which the same is mounted, and a casing surrounding and sealing the rotor element; of means for providing a cooling fluid, said means comprising a portion of the casing through which the shaft passes and adapted to seal said casing thereat and also mechanism cooperating with the casing portion for producing pressure on the cooling fluid and driven by said shaft; and connections between the rotor and the means for providing a cooling fluid adapted to circulate said fluid through the said rotor under the pressure developed by the said fluid-providing means.

2. The combination with a gaseous reaction turbine including a rotor element provided with supply and return ducts for a cooling fluid, a rotatable shaft on which the rotor is mounted, said shaft having a pair of longitudinal ducts communicating with the supply and return ducts of the rotor member, and a sealed casing surrounding the rotor element and through which the shaft passes; of means for providing a cooling fluid and embodying a portion of the casing through which the shaft passes to seal the same thereat and also an element cooperating with the said casing portion and driven by the rotor shaft for circulating the cooling fluid through

said shaft ducts and the supply and return ducts of the rotor element.

3. The combination with a gaseous reaction turbine including a rotor element provided with supply and return ducts for a cooling fluid, a rotatable shaft on which the rotor is mounted, said shaft having a pair of longitudinal ducts communicating with the supply and return ducts of the rotor member, and a sealed casing surrounding the rotor element and through which the shaft passes; of centrifugal pumping means driven by the shaft and embodying a portion of the casing through which the shaft passes to seal the same thereat and adapted to circulate a cooling fluid through the shaft ducts and the supply and return ducts of the rotor element.

In testimony whereof I affix my signature.

20 WILLIAM SPENCER BOWEN.
